CLAIM

The ornamental design for an electric motorbike battery compartment, as shown and described.

DESCRIPTION

FIG. 1 is a rear end and left side perspective view of an electric motorbike battery compartment;

FIG. 2 is a front end elevational view thereof;

FIG. 3 is a rear end elevational view thereof;

FIG. 4 is a left side elevational view thereof;

FIG. 5 is a right side elevational view thereof;

FIG. 6 is a top plan view thereof;

FIG. 7 is a rear end and left side perspective view thereof with a cover of the compartment opened;

FIG. 8 is a front end elevational view thereof with the cover of the compartment opened;

FIG. 9 is a rear end elevational view thereof with the cover of the compartment opened;

FIG. 10 is a left side elevational view thereof with the cover of the compartment opened;

FIG. 11 is a right side elevational view thereof with the cover of the compartment opened; and,

FIG. 12 is a top plan view thereof with the cover of the compartment opened.
